MERCURY SWITCH

Carl H. Larson, Elkhart, Ind., assignor to The
Adlake Company, a corporation of Illinois

Application September 1, 1933, Serial No. 687,742

29 Claims. (Cl. 200—97)

This invention relates to a time delay relay in which a mercury switch serves to make or break an electrical circuit at given intervals of time after the functioning of the switch actuating mechanism.

The time delay relays which have heretofore been used have either been large and cumbersome mechanical relays using clock mechanism where long time delays are required or tilting mercury switch relays in which an obstruction is used to impede the longitudinal flow of mercury toward or away from closed circuit position. The mechanical relays, in addition to being massive, are very expensive, while the tilting mercury switch relays are inaccurate and severely limited in the time delay which they are capable of effecting.

The principal objects of this invention, therefore, are to provide a relay which is far simpler in construction, much less expensive to manufacture and more accurate and reliable in operation than either of the two types of relays above mentioned; which has a wide range of time delays that it is capable of effecting; which can produce substantially equal time delays when closing or opening a circuit, or unequal time delays, according to requirements; and which is also capable of delaying the closing of a circuit for a given period of time after it has been acted upon by a control circuit but immediately opens the circuit when the original condition of the control circuit is restored.

Further and other objects and advantages of this invention will become apparent, as the disclosure proceeds, and the description is read in conjunction with the accompanying drawings, in which—

Fig. 1 is a sectional view illustrating the open circuit position of a slow make quick break front contact relay;

Fig. 2 shows the action which takes place immediately after energizing the relay coil;

Fig. 3 shows the closed circuit position of the switch;

Fig. 4 illustrates the momentary carrying up of the mercury within the switch plunger when the relay coil is de-energized;

Fig. 5 is a perspective view of the plunger;

Figs. 6 and 7 illustrate how the switch of Figs. 1 to 4, inclusive, may be converted into a slow make retarded break switch by merely lowering the position of the air gap;

Fig. 8 shows a slow make slow break switch immediately after the plunger has been pulled down by the coil;

Fig. 9 illustrates how a time delay is effected

in breaking the circuit using the switch of Fig. 8; Fig. 10 is a perspective view of the plunger shown in Figs. 8 and 9;

Figs. 11, 12 and 13 are views illustrating a slow make quick break contact relay, Figs. 11 and 13 showing the closed circuit and open circuit positions, respectively, of the switch, and Fig. 12 showing the momentary carrying up of mercury within the plunger when the associated relay coil is energized.

Fig. 14 shows the switch of Figs. 11 to 13, inclusive, adjusted for effecting a slow break of the circuit, as well as a slow make;

Fig. 15 illustrates a slight modification of the switch of Fig. 14, the slot at the bottom of the plunger being omitted; and

Fig. 16 illustrates how a circuit may be immediately broken upon energization of the coil by lifting the plunger completely out of the mercury.

At the outset, it should be understood that any and all specific description found in this specification is for the purpose of disclosure and should not be interpreted as imposing limitations upon the appended claims, unless required by the prior art.

Terminology

Throughout this specification the following terms are to be given the indicated connotations:

Front contact relay. A relay in which the electrical circuit is open when the associated relay coil is de-energized.

Back contact relay. A relay in which the electrical circuit is closed when the associated relay coil is de-energized.

Slow make relay. A relay in which there is a time delay between the functioning of the switch actuating mechanism and the closing of the electrical circuit controlled by the relay.

Slow break relay. A relay in which there is a time delay between the functioning of the switch actuating mechanism and the opening of the electrical circuit controlled by the relay.

Retarded break relay. A relay in which there is a time interval between the functioning of the switch actuating mechanism and the opening of the circuit, but in which the actual breaking of the circuit is accomplished by a quick separation of the conductors at the moment when the circuit is opened.

Front contact relay, slow make, quick break—
(Figs. 1 to 5)

In Fig. 1 the reference character 10 designates a relay coil which includes a spool 11 of insu-

11

lating material on which the coil is wound. The spool has a central aperture adapted to receive pole sleeves 12 and 13 of magnetic material, preferably Swedish iron. The sleeves are separated by 5 an air gap 14 and are held in adjusted position by clips 15, or equivalent means.

Telescopically mounted within the sleeves 12 and 13 is a switch 16 comprising a glass envelope 17 through the bottom of which electrodes 18 and 10 19 are sealed. The central electrode 18 is surrounded by an insulating sleeve 20 which extends to a point 21 just below the top of the electrode.

The envelope is filled to a given level with a 15 quantity of mercury 22 and the condition of the electrical circuit between the electrodes 18 and 19 is determined by the level of the mercury.

The displacer or plunger 23 of magnetic material normally floats upon the mercury, as shown in Fig. 1, but is adapted to be drawn downwardly 20 through magnetic influence to raise the mercury level and electrically connect the electrodes 18 and 19. The top of the displacer is interiorly fitted with a metal sleeve 24 which carries a porous thimble 25 at its upper end. Preferably, 25 the thimble is made of a ceramic material, known as alundum, which is manufactured by the Norton Company of Worcester, Massachusetts. One of the three principal grades, R-A-84 dense, R-A-360 medium and R-A-98 coarse, may be 30 selected according to the specification of the switch.

Obviously, the metal sleeve 24 may be omitted, if desired, and the ceramic thimble 25 attached directly to the plunger or displacer 23.

35 A slot 26 is cut in the upper side wall of the plunger and extends to a point slightly below the bottom edge of the sleeve 24. Any kind of an opening immediately below the bottom of the sleeve would do as well.

40 In order to increase the buoyancy of the plunger, it is desirable to equip the bottom of the plunger with a ceramic insert 27 which may be of glass, alundum or other suitable material.

45 Coil springs 28 and 29 made of non-magnetic material are provided to protect the switch envelope from damage during shipment. Preferably, the plunger 23 is made with sufficient buoyancy so when the coil 10 is de-energized, the spring 28 will be slightly compressed by the 50 plunger.

55 After the displacer with its associated parts and the mercury have been placed in the switch envelope, the switch is evacuated and a suitable gas fill is inserted, such, for example, as helium, hydrogen or helium hydride. Thereafter, the top of the switch envelope is sealed off, in accordance with the usual practice.

60 The switch is shown in Fig. 1 in its normal de-energized state with the circuit between the electrodes 18 and 19 broken.

65 As soon as the relay coil is energized, the switch plunger 23 is lowered to the position shown in Fig. 2 because the air gap 14 is traversed by a strong magnetic field and the plunger moves to a position which reduces the air gap to a minimum.

70 As the plunger starts on its downward movement, the mercury level on both the inside and outside of the plunger begins to rise due to the displacement of mercury by the plunger. As soon as the mercury level within the plunger reaches the bottom of the sleeve 24 the gas entrapped within the thimble forces the mercury away from the bared portion of the electrode 18, 75 while the mercury level on the outside is being raised due to further displacement of the mer-

cury by the plunger. This is clearly shown in Fig. 2.

The porous material of which the thimble 25 is composed allows the entrapped gas to slowly escape from the plunger, and as this happens the 80 mercury levels on the inside and outside of the plunger tend to equalize. The time which is required for the equalization to take place depends upon the porosity of the ceramic material, but eventually the mercury assumes a common 85 level on both the inside and outside of the plunger, as shown in Fig. 3. Obviously, as soon as the mercury level within the plunger rises above the top of the insulating sleeve 20, the electrical 90 circuit through the electrodes 18 and 19 is completed.

When the coil 10 is de-energized, the buoyancy 95 of the plunger causes it to rise to the position shown in Fig. 4. Momentarily, mercury is carried upwardly within the sleeve 24 due to the inability of the gas to enter the plunger through the ceramic thimble fast enough to maintain equal pressures on the inside and outside of the thimble. However, as soon as the mercury level on the outside drops below the bottom of the slot 100 26, gas can enter the plunger through the small opening beneath the sleeve 24, which results in the mercury column within the plunger being undermined, and the mercury levels on both the inside and outside of the plunger quickly fall to the 105 common level at which they are shown in Fig. 1.

It will, therefore, be seen that the switch shown in Figs. 1 to 5 inclusive effects a slow making of the electrical circuit between the electrodes 18 and 19 when the coil 10 is energized, but thereafter, on de-energizing the coil, the plunger rises 110 immediately to its normal position, shown in Fig. 1, thus promptly breaking the electrical circuit, although, momentarily, mercury is carried up within the plunger, as shown in Fig. 4. 115

*Front contact relay, slow make, retarded break—
(Figs. 6 and 7)*

By merely lowering the position of the air gap 14, the switch shown in Figs. 1 to 5, inclusive, may 120 be made to operate as a slow make retarded break switch. This may be explained as follows: When the plunger is lowered by the coil 10, it is pulled deeper (Fig. 6) into the mercury than at first, due to the lowered position of the air gap. Consequently, when the mercury levels off after sufficient time has elapsed for the necessary volume of gas to pass from the plunger through the thimble 25, the common level will be substantially 125 above that in which it was shown in Fig. 3. 130 This level is indicated by dotted line in Fig. 6.

Thereafter, when the coil is de-energized, an 135 amount of mercury will be carried up by the plunger, which, added to the weight of the plunger itself, will not permit the buoyancy of the plunger to lift the bottom of the sleeve 24 above the outside mercury level, as indicated in Fig. 7, but as gas enters the plunger through the thimble 25, the mercury level within the plunger recedes, thereby diminishing the weight of the plunger and causing the latter to slowly rise, the outside mercury level, however, remaining constant. As soon as sufficient gas has entered through the thimble, the bottom of the sleeve 24 will be carried above the outside mercury level, whereupon the mercury 140 column within the sleeve will be undermined and the circuit through the electrodes 18 and 19 quickly broken.

145 The movement of the plunger when the coil is de-energized is characterized by a preliminary 150

quick movement which establishes the position of equilibrium between the plunger and the mercury, then a relatively slow movement as gas gradually enters the plunger through the porous thimble 5 and finally the quick movement as the mercury column within the plunger is undermined, allowing the plunger to rise to its uppermost position.

*Front contact relay, slow make, slow break—
(Figs. 8 and 9)*

10 From the description of the slow make retarded break relay, it is apparent that if the slot 26 were omitted, the switch would function as a slow make, slow break relay. The same result, however, can 15 be obtained by using a plunger of somewhat simpler construction.

In Figs. 8 and 9, the switch 30 differs principally from the switch 16 in having a shorter central electrode 31 and further by being provided with 20 a plunger 32 in which the ceramic thimble 33 is fitted directly into the top of the plunger. The side walls of the plunger are imperforate so that gas can enter the plunger only through the thimble 33.

25 The position of the switch parts immediately after the coil has been energized is shown in Fig. 8 and the dotted line 34 in the same figure indicates the mercury level after the coil has been energized and sufficient time has elapsed to permit the inside and outside mercury levels to 30 equalize.

Upon deenergizing the coil 10, the plunger 32 rises to the position shown in Fig. 9 carrying a column of mercury upwardly within the plunger. 35 This column slowly recedes as gas enters the plunger through the thimble 33 and at the same time the plunger slowly rises as its effective weight is reduced. As soon as the mercury falls below the top of the insulation which surrounds the 40 electrode 31, the electrical circuit controlled by the relay is broken.

It is obvious that the relative time delays on making and breaking the circuit may be varied within limits by adjusting the position of the air 45 gap, the height of the central electrode, the mercury fill, etc.

Back contact, slow make, quick break—(Figs. 11 to 13, inclusive)

50 In a back contact relay, it will be remembered the electrical circuit is closed when the relay coil is deenergized. Thus in Fig. 11 the plunger 40 has sufficient weight to bring the mercury level to above the top of the insulating sleeve 41 which 55 surrounds the central electrode 42, thereby causing the electrical circuit through the electrodes 42 and 43 to be closed. The pole sleeves 44 and 45 are so positioned that when a magnetic field passes between the two sleeves, the plunger 40 will be 60 lifted to the position shown in Fig. 12 and will remain there as long as the coil is energized. In the switch shown in Figs. 11 to 13, a slot 46 is provided in the side wall of the plunger so that when the plunger is raised to the position shown 65 in Fig. 12 the top of the slot will be lifted above the outside mercury level, thus causing the column of mercury within the plunger to be undermined and fall away from the electrode 42. When this occurs, the mercury level will be substantially as shown in Fig. 13.

70 Obviously, when the relay afterward is deenergized, the plunger 40 will fall by gravity to a position somewhat above that shown in Fig. 11, 75 forcing mercury away from the central electrode

because of the entrapment of gas within the plunger. As the gas slowly escapes through the thimble 47, the mercury will rise to a sufficient height to cover the central electrode and establish a circuit between the electrodes 42 and 43. 80

*Back contact relay, slow make, slow break—
(Figs. 14 and 15)*

The switch shown in Fig. 14 is identical with the one shown in Figs. 11 to 13, inclusive, but the air gap between the pole sleeves 44 and 45 is somewhat lower relative to the plunger so that the slot 46 of the plunger is not uncovered when the plunger is raised by energizing the relay coil. In this way, the mercury actually carried up by the plunger recedes slowly as gas is admitted to the interior of the plunger and thereby effects a slow breaking of the electrical circuit. 90

Upon dropping the plunger by releasing the magnetic force, mercury is pushed away from the central electrode due to the entrapment of gas within the plunger, but the slow escape of gas through the thimble 47 permits the inside and outside levels to equalize, and finally establish the circuit. 95

Since the slot 46 serves no useful purpose when the air gap is arranged, as shown in Fig. 14, it may be eliminated, as shown in Fig. 15, giving a wider range for adjustment of the air gap and a consequent lengthening of the time delays. 100

*Back contact relay, slow make, quick break—
(modified form Fig. 16)*

In Fig. 16 a back relay is shown in which the plunger 48 is adapted to be lifted completely out of the mercury whenever a magnetic field traverses the air gap 49 between the pole sleeves 50 and 51. The plunger is equipped with a ceramic lining 52 which projects below the bottom of the plunger wall and is adapted to have a coil spring 53 fitted over its projecting end. A similar spring 54 is fitted over the ceramic thimble 55 which closes the opening 56 at the top of the plunger. 110

The ceramic sleeve 52 materially increases the buoyancy of the plunger and makes it unnecessary 120 to lift the plunger but a slight distance in order to break the circuit. When the coil is deenergized, the plunger drops into the mercury and slowly permits the mercury around the central electrode 57 to rise and connect the bared portion 125 of the electrode with the conductor 58.

In all forms of the relay, the plungers are preferably provided with lugs 59, as best shown in the perspective views of Figs. 5 and 10. The lugs serve to guide the plunger in its vertical travel 130 within the switch envelope.

Instead of using a thimble of porous material at the top of the plungers to obtain a slow gas leakage, a small opening could be provided having the appropriate diameter for a given time delay. 135 If a relatively long time delay is required, the opening may be restricted by inserting a tapered plug, which permits the size of the opening to be varied according to the position of the plug in the opening.

It will be observed that the principal purpose of the slots in the side walls of the plungers is to provide suitable openings for controlling the amount of gas which is admitted into a plunger. However, the slots also serve to minimize eddy 140 currents when the relay is operating on alternating current, and, consequently, require less power for operation.

The ceramic thimbles which are fitted into the tops of the plungers are preferably cemented in 150

place with dental cement. Fine adjustment of time delay may be obtained by daubing the exposed part of the thimble with cement until time delay is brought down to specification.

5. What I claim, therefore, is:

1. In a mercury switch adapted to effect a slow make and quick break of an electrical circuit when associated with a relay coil, the combination of a vertical switch envelope, spaced electrodes in the envelope, a charge of mercury adapted to open or close an electrical circuit through the electrodes according to its level, a plunger movable within the envelope in response to the coil for changing the mercury level, said

10 plunger being telescoped over one of the electrodes and closed at the top except for one or more restricted openings so that when the plunger is lowered, mercury is held away from said electrode for a given time interval, said plunger also

20 having an opening positioned so that when the plunger is in its raised position, the mercury column carried upwardly within the plunger is undermined and immediately falls away from the said electrode.

25 2. In a mercury switch adapted to effect a slow make and quick break of an electrical circuit when associated with a relay coil, the combination of a vertical switch envelope, spaced electrodes in the envelope, a mercury fill adapted to make or break an electrical circuit through the electrodes according to its level, a plunger movable within the envelope in response to the coil for changing the mercury level, and means adapted to retard the movement of the mercury

35 to one of said electrodes, and means for undermining the mercury column around said electrode as soon as the plunger is moved to its raised position.

3. In a mercury switch adapted to effect a slow make and quick break of an electrical circuit when associated with a relay coil, the combination of a vertical switch envelope, spaced electrodes in the envelope, a mercury fill adapted to make or break an electrical circuit through the electrodes according to its level, a plunger movable within the envelope in response to the coil for changing the mercury level, and means carried by the plunger adapted to retard the movement of the mercury to one of said electrodes, and means for undermining the mercury column around said electrode as soon as the plunger is moved to its raised position.

4. In a mercury switch adapted to effect a slow make and quick break of an electrical circuit when associated with a relay coil, the combination of a vertical switch envelope, spaced electrodes in the envelope, a charge of mercury adapted to make or break an electrical circuit through the electrodes according to its level, a plunger movable within the envelope in response to the coil for changing the mercury level, said plunger normally floating on the mercury and displacing an insufficient quantity of mercury to bridge the electrodes when the relay coil is de-energized, means adapted to retard the movement of mercury to one of said electrodes, and means for undermining the mercury column around said electrode as soon as the plunger is allowed to rise to its floating position by de-energization of the coil thereby causing a quick breaking of the circuit.

5. In a mercury switch adapted to effect a slow make and quick break of an electrical circuit when associated with a relay coil, the combination of a vertical switch envelope, spaced elec-

trodes in the envelope, a charge of mercury adapted to make or break an electrical circuit through the electrodes according to its level, a plunger movable within the envelope in response to the coil for changing the mercury level, said plunger normally displacing a sufficient quantity of mercury to bridge said electrodes when the relay coil is de-energized, means adapted to retard the movement of mercury to one of said electrodes, and means for undermining the mercury column around said electrode as soon as the plunger is allowed to rise to its floating position by de-energization of the coil thereby causing a quick breaking of the circuit.

6. In a mercury switch adapted to effect a slow make and quick break of an electrical circuit when associated with a relay coil, the combination of a vertical switch envelope, spaced electrodes in the envelope, a charge of mercury adapted to make or break an electrical circuit through the electrodes according to its level, a plunger movable within the envelope in response to the coil for changing the mercury level, said plunger being telescoped over one of the electrodes and having one or more restricted openings adjacent to its top whereby the movement of mercury to and away from the said electrode is retarded by the unequal gas pressures on the inside and outside of the plunger, said plunger also having an opening positioned so that when the plunger is in its raised position, the mercury column carried upwardly within the plunger is immediately undermined and falls away from the said electrode.

7. In a mercury switch adapted to effect a slow make and quick break of an electrical circuit when associated with a relay coil, the combination of a vertical switch envelope, spaced electrodes in the envelope, a charge of mercury adapted to make or break an electrical circuit through the electrodes according to its level, a plunger movable within the envelope in response to the coil for changing the mercury level, means for retarding the movement of mercury to and away from one of said electrodes when the mercury level is changed by movement of the plunger, said plunger having an opening in one of its side walls positioned so that when the plunger is in its raised position, the mercury column carried upwardly within the plunger is undermined and immediately falls away from said electrode.

8. A plunger for use in a mercury switch of the class described, comprising a tubular body at least a portion of which is made of magnetic material, said plunger being closed at the top except for one or more restricted openings, said plunger also having an opening piercing the side wall of the plunger at a point slightly above the mercury level line of normal floating position.

9. A plunger for use in a mercury switch of the class described, comprising a tubular body at least a portion of which is made of magnetic material, a porous wall in the upper part of the plunger, said plunger being provided with an opening which pierces the side wall of the plunger at a point slightly above the mercury level line of normal floating position.

10. In a mercury switch adapted to effect a slow make and a somewhat faster break of an electrical circuit when associated with a relay coil, a combination of a vertical switch envelope, spaced electrodes in the envelope, a charge of mercury adapted to open or close an electrical circuit through the electrodes according to its level, a plunger movable within the envelope in

- response to the coil for changing the mercury level, said plunger being telescoped over one of the electrodes and closed at the top except for one or more restricted openings so that when the 5 plunger is lowered upon energization of the coil, mercury is held away from said electrode for a given time interval, said plunger also having an opening positioned so that when the plunger is released by de-energization of the coil, it will 10 levitate by first a quick movement, then a retarded movement, and lastly by another quick movement, which latter movement effects a substantially instantaneous opening of the circuit.
11. In a mercury switch adapted to effect a slow make and slow break of an electrical circuit when associated with a relay coil, the combination of a vertical switch envelope, spaced electrodes in the envelope, a mercury fill adapted to make or break an electrical circuit through 15 the electrodes according to its level, a plunger movable within the envelope in response to the coil for changing the mercury level and means for retarding the movement of the mercury to and from one of said electrodes, said means comprising a porous wall adjacent to the top of the plunger.
12. In a mercury switch, a sealed vertical envelope, spaced electrodes in the envelope, a gas fill, a charge of mercury adapted to close or open 20 a circuit across the electrodes, according to its level, a displacer movable within the envelope to displace the mercury, said displacer being hollow and telescopically movable over one of the electrodes, and a porous wall in the upper part 25 of the plunger for delaying movement of the mercury column within the displacer.
13. In a mercury switch, a switch envelope, spaced electrodes in the envelope, a gas fill, a quantity of mercury in the envelope adapted to 30 be manipulated to make or break an electrical circuit through the electrodes, an inverted cup-shaped member provided with a porous wall adjacent to the top for retarding the movement of mercury within the member, in at least one direction, by the gas pressure differential existing between the interior and exterior of the member, said electrodes being arranged so that the condition of the circuit is determined by the height 35 of the mercury within the member with respect to a fixed point on the envelope.
14. In a mercury switch, a switch envelope, spaced electrodes in the envelope, a gas fill, a quantity of mercury in the envelope adapted to be manipulated to make or break an electrical 40 circuit through the electrodes, an inverted cup-shaped member telescoped over one of the electrodes and presenting a relatively large opening to the mercury and a limited opening to the gas, said latter opening consisting of a porous wall adapted to pass gas but slowly, means for changing 45 the mercury level on the outside of the member whereby movement of the mercury within the member in at least one direction is retarded by the restricted flow of gas through the porous wall.
- 50 15. In a mercury switch, a switch envelope, spaced electrodes in the envelope, a gas fill, a mercury fill adapted to be manipulated to make or break an electrical circuit through the electrodes, a displacer normally displacing a sufficient quantity of mercury to bridge the electrodes, but being adapted to be raised by magnetic force completely out of the mercury whereby the 55 connection between the electrodes is broken, and means including a restricted gas passage for delaying the movement of mercury toward one of
- the electrodes when the displacer is dropped from its raised position.
16. In a mercury switch, a stationary switch envelope, spaced electrodes in the envelope, a gas fill, a mercury fill adapted to be manipulated to make or break an electrical circuit through the electrodes, and means for retarding the movement of the mercury to effect a given time delay in changing the condition of the electrical circuit, said means including a porous wall, and means for creating unequal gas pressures on opposite sides of the wall without moving the switch envelope.
- 80 17. In a mercury switch, a stationary switch envelope, spaced electrodes in the envelope, a gas fill, a mercury fill adapted to be manipulated to make or break an electrical circuit through the electrodes, and means for producing a time delay in changing the condition of the electrical circuit in the switch without moving the switch envelope, said means including a porous wall interposed between the gas fill and a column of mercury moving to and away from one of the electrodes, so that the retarded passage of gas through the wall will cause a corresponding retarded movement of the mercury column in at least one direction.
- 90 18. In a mercury switch, a stationary switch envelope, spaced electrodes in the envelope, a gas fill, a mercury fill adapted to be manipulated to make or break an electrical circuit through the electrodes, and means for producing a time delay in changing the condition of the electrical circuit in the switch without moving the switch envelope, said means including a porous wall 95 interposed between the gas fill and a column of mercury moving to and away from one of the electrodes, so that the retarded passage of gas through the wall will cause a corresponding retarded movement of the mercury column in at least one direction.
- 100 19. In a mercury switch, a stationary switch envelope, spaced electrodes in the envelope, a gas fill, a mercury fill adapted to be manipulated to make or break an electrical circuit through the electrodes, and means for retarding the passage of gas therethrough and in consequence retarding the flow of mercury to circuit opening or circuit closing position.
- 110 20. In a mercury switch, a sealed vertical envelope, spaced electrodes in the envelope, a gas fill, a charge of mercury adapted to close or open a circuit across the electrodes, according to its level, a displacer movable within the envelope to displace the mercury, and means for retarding movement of a portion of the mercury to effect a given time delay in changing the condition of the electrical circuit, said means including a porous wall through which gas is slowly passed by unequal pressures developed on opposite sides of the wall by the movement of the remainder of the mercury.
- 120 21. In a mercury switch, a sealed vertical envelope, spaced electrodes in the envelope, a gas fill, a charge of mercury adapted to close or open a circuit across the electrodes, according to its level, means for forming a gas trap around one of the electrodes to effect a given time delay, said means including a displacer for shifting the mercury and a porous wall for relieving pressure in the trap.
- 130 22. In a mercury switch, a sealed vertical envelope, spaced electrodes in the envelope, a gas fill, a charge of mercury adapted to close or open a circuit across the electrodes, according to its level, means for forming a gas trap around one of the electrodes to effect a given time delay, said means including a displacer for shifting the mercury and a porous wall for relieving pressure in the trap.
- 135 23. In a mercury switch, a sealed vertical envelope, spaced electrodes in the envelope, a gas fill, a charge of mercury adapted to close or open a circuit across the electrodes, according to its level, means for forming a gas trap around one of the electrodes to effect a given time delay, said means including a displacer for shifting the mercury and a porous wall for relieving pressure in the trap.
- 140 24. In a mercury switch, a sealed vertical envelope, spaced electrodes in the envelope, a gas fill, a charge of mercury adapted to close or open a circuit across the electrodes, according to its level, means for forming a gas trap around one of the electrodes to effect a given time delay, said means including a displacer for shifting the mercury and a porous wall for relieving pressure in the trap.
- 145 25. In a mercury switch, a sealed vertical envelope, spaced electrodes in the envelope, a gas fill, a charge of mercury adapted to close or open a circuit across the electrodes, according to its level, means for forming a gas trap around one of the electrodes to effect a given time delay, said means including a displacer for shifting the mercury and a porous wall for relieving pressure in the trap.
- 150

- a circuit across the electrodes, according to its level, a displacer telescoped over one of the electrodes for changing the mercury level, and porous material closing the top of the displacer whereby
- 5 a gas trap of slow leakage is formed over the said electrode when the displacer is lowered.
23. In a mercury switch, a sealed vertical envelope, spaced electrodes in the envelope, a gas fill, a charge of mercury adapted to close or open
- 10 a circuit across the electrodes, according to its level, a displacer movable within the envelope to displace the mercury, said displacer having a tubular body telescopically movable over one of said electrodes, and porous material closing the top of
- 15 the displacer.
24. A displacer for use in a time delay mercury switch comprising a tubular body, at least a portion of which is of magnetic material, and a porous wall in the upper part of the displacer.
- 20 25. A plunger for use in a mercury switch of the class described comprising a tubular body at least a portion of which is of magnetic material, and a porous wall in the upper part of the plunger adapted to pass gas relatively slowly therethrough.
- 25 26. A plunger for use in a switch of the class described comprising a sleeve of magnetic material having an inverted cup-shaped sleeve interiorly mounted in the first named sleeve, said inner sleeve including a porous wall.
- 30
27. A plunger for use in a switch of the class described comprising an outer sleeve of magnetic material having a uniform external diameter slightly less than the internal diameter of the switch envelope, guide lugs on the sleeve for maintaining it at the appropriate distance from the envelope, and an inverted cup-shaped sleeve, interiorly mounted in the first named sleeve, said inner sleeve including a porous wall.
28. In combination with a coil, a mercury switch comprising a vertical switch envelope, spaced electrodes in the envelope, a mercury fill, a displacer including magnetic material acting in response to the coil for changing the mercury level, and means for retarding the movement of a portion of the mercury to effect a given time delay, said means including an inverted cup-shaped element provided with a porous wall and arranged to form a pocket over said electrode.
29. A plunger for use in a mercury switch of the class described comprising a tubular body at least a portion of which is of magnetic material, a porous wall in the upper part of the plunger adapted to pass gas relatively slowly therethrough, and a dab of cement applied to the porous wall for restricting the rate of gas flow through the wall.
